UNITED STATES PATENT OFFICE.

HANS GEORGE WILLIAM CARSTENS AND HANS FREDRICK PETERS, OF MOLINE, ILLINOIS.

EGG-TESTER.

SPECIFICATION forming part of Letters Patent No. 576,808, dated February 9, 1897.

Application filed September 23, 1896. Serial No. 606,734. (No model.)

To all whom it may concern:

Be it known that we, HANS GEORGE WILLIAM CARSTENS and HANS FREDRICK PETERS, citizens of the United States of America, and 5 residents of Moline, in the county of Rock Island and State of Illinois, have invented certain new and useful Improvements in Egg-Testers, of which the following specification contains a full, clear, and exact description, 10 reference being had to the accompanying drawings, forming part thereof, and in which—

Figure 1 is a perspective of our improved egg-tester. Fig. 2 is a central vertical cross- 15 section on line 2 2 of Fig. 3, and Fig. 3 is a similar view on line 3 3 of Fig. 2.

Our invention relates to that class of egg-testers in which there is a casing provided with an aperture for the egg and a source of 20 light.

The object of the invention is to provide an egg-tester of the class referred to which shall be reliable, simple, and inexpensive in its construction and which may be readily 25 taken apart for cleaning.

The invention will first be described, and then specifically pointed out in the claims.

A represents the lamp-bowl, provided with a suitable burner B, and C is the lamp-chimney. Upon the upper side of the bowl A are 30 formed or secured parallel guideways A' A' at opposite sides of the burner.

D is a metallic casing having its front closed, except where it is apertured to receive an egg, 35 as shown at d, and having its rear side open. This casing D is mainly cylindrical and is formed at its open under side with parallel vertical sides D' D', the lower edges of which are flanged, as at d', to slide in the guideways A' A'.

The rear open end of the cylindrical portion of the casing D is closed by a removable cap A², provided with a knob a², but the end of the casing below this cap is open, so as to 45 afford ready access to the wick-operating shaft of the burner and provide for admission of air to the burner.

The top of the casing D is provided directly 50 above the burner with a chimney-aperture A³, down through which the chimney may be inserted and removed. This chimney B is

larger at its bottom than at its top, and hence the loose cover E is provided to close the said aperture A³ around the chimney and keep the light from passing therethrough. The 55 said cover E is free to slide on top of the casing, so that the chimney may always stand perpendicular without any nice adjusting of the casing D.

F is an opaque tube formed of metal or 60 other suitable material and surrounding the lamp-chimney, so as to still further prevent the escape of light, and this tube may simply rest at its lower end on the cover E or it may be secured thereto in any suitable manner. 65

G is a vertical reflector substantially semi-circular or U shape and mounted at its lower edge in one of the chimney-retaining prongs on the burner, so that its front edges will approach near to or contact with the closed 70 front end of the casing D, while its upper end lies close to the top of said casing, and thus the light from the burner cannot escape from around the reflector, but will all be reflected toward the egg-opening d. Thus a 75 powerful light will be afforded and it will not be necessary to use the tester in a dark room, but it may be used successfully in any room or place.

To remove the casing D, the chimney is first 80 lifted off, together with the cover E and tube F. Then remove the cap A², and then slide the casing D forwardly until it is disengaged from the guideways A' A'. The reflector may then be lifted off and all of the parts thoroughly cleaned. 85

The casing D will not become highly heated and injure the eggs, as would be the tendency where simply a metallic chimney was applied to a lamp-burner in lieu of its glass chimney 90 and provided with an egg-aperture. The heated air within the casing is free to escape upwardly through the opaque tube F, and overheating is thereby prevented.

What we claim is—

1. An egg-tester, comprising a lamp, a removable bottomless casing mounted to slide horizontally on and off the lamp-bowl and inclosing the burner; said casing having an egg-opening in its closed front end and provided with means for closing its open rear end, substantially as set forth. 95
100

2. An egg-tester comprising a lamp, a removable bottomless casing mounted to slide horizontally on and off the lamp-bowl and inclosing the burner; said casing having an egg-opening in its closed front end and provided with means for closing its open rear end, and a reflector within the casing, separate therefrom and supported from the lamp-burner, substantially as set forth. 5
- 10 3. An egg-tester, comprising a lamp, a casing mounted thereon, and having an egg-opening in its front and a chimney-opening in its top through which the chimney may be inserted and removed, an opaque tube surrounding the chimney above the casing and having a flange at its lower end resting loosely upon the top of the casing to close the opening in the top thereof around the chimney, substantially as described. 15
- 20 4. An egg-tester, comprising a lamp, a casing mounted on the lamp-bowl and inclosing the burner, the closed front end of the casing being provided with an egg-opening and the open rear end provided with a removable cap and open below the cap to admit air and permit the wick to be operated, a reflector within the casing and carried by the lamp-burner, and a removable opaque tube surrounding the chimney above the top of the casing, substantially as described. 25
- 30 5. An egg-tester, consisting in the lamp provided with parallel guideways on its bowl, and a casing having flanges or guides at its lower edges working in said guideways to permit it to be slid on and off of the bowl; the 35 front of the casing being provided with an egg-opening, the top with a chimney-opening, and the rear end with a removable cap, substantially as described. 40
6. The egg-tester, consisting in the lamp having parallel guideways on the upper side of its bowl, the casing having parallel flanges fitting said ways to permit the casing to be slid on and off, said casing also having an egg-opening in its front, a chimney-opening in its top and a removable cap at its back, and the removable opaque tube surrounding the chimney above the casing and having a flange or cover at its lower end, substantially as described. 45
7. An egg-tester consisting in the lamp having guideways on its upper side, a casing having flanged lower edges working in said guideways to permit of its being slid on and off; the front of the casing being provided with an egg-opening, the top having a chimney-opening and the back provided with a removable cap, a reflector mounted on the burner with its vertical front edges extending toward the front of the casing, an opaque tube surrounding the chimney, and a cover-flange at the lower end of said tube and resting loosely on top of the casing, substantially as described. 50
